UNITED STATES PATENT OFFICE

WINIFRED W. BEACH, OF NEW YORK, N. Y.

HAT

Application filed March 14, 1931. Serial No. 522,675.

The object of the invention is to provide a hat for women of a novel type and which I term an "awning" hat in that it comprises a bonnet-like brim to which is applied a cord or ribbon which serves as an adjusting member so that the bonnet-like brim may be drawn upwardly and held in folded position so that the hat, when the ribbon or cord is tied, has the brim so held that the face and forehead of the wearer is exposed.

I am aware that hats have heretofore been designed comprising crown connected to bonnet-like brims and made of such material that the brims may be pulled downwardly over the face or folded upwardly and held in such position by the stiffness of the material, and I make no claim to such construction, my combination including a cord or ribbon so arranged as to hold the brim in draped position above the face and forehead of the wearer and also adapted to permit the brim to be dropped so as to shield the forehead and face.

The invention will be described with reference to the accompanying drawings in which

Fig. 1 is a side elevation of an embodiment of the invention on the head of a wearer, the brim being shown in downward position to shield the face of the wearer, and the hat having the appearance of a bonnet, and

Fig. 2 is a view of said embodiment with the brim held upwardly in draped position above the face and forehead of the wearer, the hat having the appearance of a cloche.

Referring to the drawings, it will be seen that the embodiment therein illustrated comprises a crown member 1 and a brim member 2 which may be integral with the crown or formed separately and united by seaming. The brim is cut with a "poke" front 2x and is continuous relatively to the base of the crown, so that it partly shields the back of the neck of the wearer. By means of such construction the hat is well adapted for beach wear and outdoor wear generally where protection from the sun is desired.

It will be noted that the brim 2 at spaced cuts is cut so as to provide loops 3 to receive a ribbon or cord 4, the cord thus being slid-

ably connected to the brim. The said loops are preferably so arranged as to enable the application of the cord to the upper surface of the brim, although this is not essential. If desired, the loops may be formed separately from the brim and applied to the latter by any suitable means.

As hereinbefore stated, when the wearer is subjected to the rays of the sun, as for example, on a beach or golf links, the hat may be worn as illustrated in Fig. 1. When, however, there is no necessity for shielding the face and forehead of the wearer the brim may be folded or draped upwardly in a manner, for example, of Fig. 2, whereupon the ends of cord 4 may be drawn and tied to hold the brim in the said draped position.

Having described my invention, what I claim and desire to secure by Letters Patent, is as follows:—

A hat comprising a crown member and a brim member formed with a forwardly projecting or "poke" front and having its edge in a continuous curved line, the poke front being adapted to be held downwardly in position to shield the face of the wearer and adapted to be draped upwardly to expose the face and forehead of the wearer, cord-receiving members secured to the brim near its free edge and a cord passing through said cord-receiving members and adapted to be drawn in such position as to hold the brim in draped position and also adapted to be secured in said drawn position, the construction being such that the poke front is held in draped position by tying said attenuated flexible member rearwardly of the hat at the base of the crown without altering the position of the brim below the poke front thereof.

In testimony whereof, I have signed my name to this specification.

WINIFRED W. BEACH.
